ARMCHAIR

Jerry Johnson, 3739 S. Rodeo Drive, Malibu, Calif.

Filed Oct. 2, 1962, Ser. No. 71,971

Term of patent 7 years

(Cl. D15—1)

FIGURE 1 is a front perspective view of an armchair showing my design, a portion of one of the leg extensions having been omitted for convenience of illustration.

FIGURE 2 is a rear perspective view of the armchair.

FIGURE 3 is a fragmentary, rear elevational view thereof on a reduced scale.

I claim:

The ornamental design for an armchair, as shown.
